O. O. STORLE.
AUTOMATIC STOP FOR GRAMOPHONES.
APPLICATION FILED FEB. 7, 1919.

1,375,120.

Patented Apr. 19, 1921.

UNITED STATES PATENT OFFICE.

OLE O. STORLE, OF TACOMA, WASHINGTON.

AUTOMATIC STOP FOR GRAMOPHONES.

1,375,120.

Specification of Letters Patent. Patented Apr. 19, 1921.

Application filed February 7, 1919. Serial No. 275,525.

To all whom it may concern:

Be it known that I, OLE O. STORLE, a citizen of the United States, residing at Tacoma, in the county of Pierce and State of Washington, have invented certain new and useful Improvements in Automatic Stops for Gramophones, of which the following is a specification, reference being had to the accompanying drawing, forming a part

10 thereof.

This invention relates to sound reproducing machines in which record disks are used having spiral grooves terminating at their inner ends in continuous circular grooves 15 of different radii according to the varying lengths of the spiral grooves of different records, and the tone arm carrying the stylus or tracing point which traverses the record grooves swings over the turn table trans- 20 versely to the grooves.

The main objects of the invention are to automatically stop machines of this type at the ends of records of different lengths; to avoid the care and trouble involved in setting or adjusting the stop mechanism for records of different lengths, and generally to simplify and improve the construction and operation of devices of this class.

It consists in the construction, arrangement and combination of parts as herein- 30 after particularly described and pointed out in the claims.

In the accompanying drawing like characters designate the same parts in the several figures.

Figure 1 is a plan view of a brake and stop mechanism embodying the invention as applied to a gramophone, parts of which are shown; Fig. 2 is a side elevation of the 40 brake and stop mechanism, the top plate and turn table of the gramophone being shown in section; and Fig. 3 is a plan view similar to Fig. 1, of a modification of the brake and stop mechanism.

Referring to Figs. 1 and 2, *a* designates the turn table having a downturned rim *b*; *c* the top plate, which serves as a base plate or support for the brake and stop mechanism, *d* the upper end of the turn table spindle, and *e* a part of the tone arm of a gramophone or sound reproducing machine of a wellknown type.

A brake lever having three arms, *f*, *g* and *h*, like or similar to those used in machines 55 of this class, is fulcrumed at the intersection of its arms on the plate *c* by a stud

or screw *i*, and is provided at the end of its arm *f* with a pad of rubber or other suitable elastic material adapted when the brake is applied, to engage with the depending rim *b* of the turn table. The arm *h*, projecting outwardly between the turn table and plate beyond the margin of the turn table, serves as a handle for manually operating the brake. A toggle joint, composed 60 of members *k* and *l* pivotally connected at one end with the plate *c* and at the other end with the arm *g* of the brake lever, is arranged when straightened, to hold the brake in off position, as shown in Fig. 1. 70 The member *k* is extended beyond its knuckle or pivot connection with the member *l*, and is formed with an upstanding projection *m*, which serves as a stop to limit the movement of the knuckle in one direction, or away from the spindle *d*, when the members are in approximate alinement with each other for locking and holding the brake lever in off position, with the pad *j* out of engagement with the rim *b* of the turn table. 75

A spring *n*, connected at one end by a pin or stud with the plate *c* and at the opposite end with the member *l* adjacent to its pivot connection with the brake lever, tends to apply the brake and to bend the toggle joint 85 in either direction from a straight line passing through its pivot connections with the plate *c* and brake lever.

A pinion *o*, having two teeth, is fixed on the spindle *d* between the turn table *a* and 90 plate *c*. A gear *p*, mounted on the plate *c* in position to mesh with the pinion *o*, is formed or provided on one side with a wide or laterally projecting tooth *q*. A spring friction washer *r*, interposed between the 95 gear and the head of the screw stud *s* on which the gear turns, prevents accidental turning or displacement of said gear when neither of the teeth of the pinion *o* are in engagement therewith. An angular hooked 100 trip arm *t* is pivotally connected at its elbow with the toggle joint by the knuckle pin connecting the members of the joint with each other, and is movable at its hooked end into and out of the path of the gear tooth *q*. 105

A segmental or sector-shaped friction wheel *u*, having an upturned rim *v*, is pivotally mounted on cone pointed pins or screws *w*, one of which is adjustable, in a forked bracket *x*, fastened to the plate *c* 110 underneath the table *a*, adjacent to the tone arm *e*. The wheel *u* is connected by a link

y with an arm z, attached to the tone arm e. A drag arm 2, pivotally mounted on the upper end of the hub of the friction wheel v or otherwise, concentrically with the pivot of the friction wheel, and resting in frictional engagement on the rim v of the friction wheel, is connected by a link 3 with the trip arm t at the end opposite the hook.

In the operation of the brake and stop mechanism as shown in Figs. 1 and 2, assuming that the brake is released and applied and the parts of the mechanism are in positions indicated by dotted lines in Fig. 1, the tracing stylus carried by the tone arm engaging the circular groove indicated by the dotted line 4, Fig. 1, at the end of a record, when the tone arm 3 is swung outwardly for changing record disks or repeating a record, the segmental friction wheel u will be correspondingly turned outward, its rim v sliding underneath the drag arm 2 and tending to swing the hooked end of the trip arm t toward and into the path of the gear tooth q. The inward movement of the tone arm necessary to carry the stylus over a record disk and enter it in the outer turn of the spiral record groove, will correspondingly turn the friction wheel u clockwise underneath and in engagement with the drag arm 2, which will be carried therewith till the trip arm t is turned outwardly away from the path of the gear tooth q into inoperative position, as approximately indicated by dotted lines in Fig. 1. The brake being then thrown manually into release or off position by means of the handle arm h, and the toggle joint thereby straightened to lock and hold the brake in that position, as shown by full lines in Fig. 1, as the spindle d rotates, the teeth of the pinion o will engage with and intermittently turn the gear p, and the friction wheel u will be slowly advanced with the tone arm e, in a clockwise direction, and will carry the drag arm 2 with it till it is arrested and pushed back by engagement with the gear tooth q which extends above it, as shown in Fig. 2. The drag arm will thus be alternately swung toward and from the spindle d, and will swing the trip arm t into and out of the path of the gear tooth q, permitting the gear tooth to clear the hooked end of the trip arm while and as long as the stylus traverses the spiral record groove and the friction wheel u is turned by the tone arm e clockwise, but when the stylus enters the circular groove 4 at the end of the spiral record groove, the movement of the tone arm and of the friction wheel u connected therewith will be arrested after the gear tooth q has pushed the drag arm back and turned the trip arm t into operative position in the path of said tooth, so that when said tooth is turned into position by a partial revolution of the gear p, it will engage with the hooked end of the trip arm, and its further rotation

by the first tooth of the pinion o will bend the toggle joint sufficiently to release the brake lever and permit the instant application of the brake by the spring n to the turn table, thereby stopping the machine. 70 The second gear tooth of the pinion o turns the gear tooth q out of position to be re-engaged by the hook n of the trip arm t, which has in the meantime been thrown by the action of the spring n in applying the 75 brake and bending the toggle joint, out of the path of said tooth, as indicated approximately by dotted lines in Fig. 1. The machine will thus be automatically stopped at the ends of records of different lengths, 80 without care or attention on the part of the operator, and without the necessity of setting or adjusting the stop mechanism for each record.

Referring to Fig. 3, showing a modification of the mechanism, the toggle joint k', l', is reversed and arranged to bend in the opposite direction for releasing the brake lever and permitting the application of the brake, as indicated by dotted lines. The trip arm t', pivotally connected at one end with the knuckle of the toggle joint, is formed at the other end with a shoulder for engagement with the tooth q, of the gear p. The actuating connection of the segmental friction 95 wheel u with the tone arm e, consists of a bent arm z', provided with a pivoted block 5, engaging a radial slot 6 in said wheel. A stop 7, limits the movement of the drag arm 2 away from the spindle d by the friction wheel u, when the tone arm 3 is turned outwardly for changing records or repeating a record. 100

In other respects the mechanism shown in Fig. 3 is substantially like that shown in Fig. 1 in construction and operation. 105

Various changes other than those shown and specifically mentioned, may be made in the construction and arrangement of parts of the brake and stop mechanism, without departure from the principle and scope of the invention as defined in the following claims. 110

I claim:

1. In an automatic stop for gramophones, the combination of a segment pinion on the turn table spindle, a gear arranged to mesh with said pinion and having a lateral projection adjacent its periphery, a brake lever, a toggle joint arranged when straightened to hold the brake in off position, a spring tending to apply the brake; a trip arm pivotally connected with the toggle joint and movable into and out of the path of the lateral projection on said gear, an oscillatory friction member having an actuating connection with the tone arm, and a pivoted drag arm engaging said friction member and connected with the trip arm, said drag arm being adapted to be alter- 115 120 125 130

- nately swung toward and from the turn table spindle by said friction member and the projection on said gear.
2. In an automatic stop for gramophones, 5 the combination with a friction brake lever, of a toggle joint arranged to lock and hold the brake in off position; a spring tending to apply the brake; a segment pinion on the turn table spindle; a gear arranged to 10 mesh with said pinion and having a laterally projecting tooth on one side; a trip arm pivotally connected with the toggle joint, movable into and out of the path of said tooth and adapted when engaged there- 15 by to shift the knuckle of the toggle joint and release the brake; an oscillatory friction wheel having an actuating connection with the tone arm; and a pivoted drag arm loosely engaged by said friction wheel and 20 connected with the trip arm, said drag arm being adapted to be alternately swung toward and from the turn table spindle by the friction wheel and said gear tooth as the stylus transverses a record groove, and 25 to carry the trip arm into and out of the path of said tooth until the stylus reaches the end of the record groove and the movement of the tone arm is thus arrested.
3. In an automatic stop for gramophones, 30 the combination with a brake lever, of a toggle joint provided with a stop to hold the brake in off position, a spring tending to apply the brake and to bend the toggle joint, a segment pinion on the turn table 35 spindle, a gear arranged to mesh with said pinion and having a laterally projecting tooth, a trip arm pivotally connected with the toggle joint, a friction wheel having an actuating connection with the tone arm of 40 the gramophone, and a drag arm pivoted concentrically with the friction wheel in frictional engagement therewith and connected with the trip arm, said drag arm being movable alternately by the friction 45 wheel and projecting gear tooth toward and from the center of the gear and serving by its connection with the trip arm to alternately shift it into and out of the path of said tooth.
- 50 4. In an automatic stop for gramophones the combination with a brake lever, of a toggle joint adapted to hold the brake in off position, a spring tending to apply the brake and bend the toggle joint, a segment 55 pinion on the turn table spindle, a gear arranged to mesh with said pinion and having a laterally projecting tooth and a friction washer, a trip arm pivotally connected with the toggle joint, a friction wheel having 60 an actuating connection with the tone arm of the gramophone, and a drag arm pivoted concentrically with the friction wheel in frictional engagement therewith and connected with the trip arm, said drag
- arm being movable into and out of the path 65 of said gear tooth, and serving by its connection with the trip arm to alternately shift it into and out of the path of said gear tooth.
5. In an automatic brake for gramophones, 70 the combination with a brake lever, of a toggle joint adapted to hold the brake in off position, a spring tending to apply the brake and to bend the toggle joint, a segment pinion on the turn table spindle 75 having a plurality of teeth, a gear arranged to mesh with the pinion and having a laterally projecting tooth, an angular hooked trip arm pivotally connected with the toggle joint and movable into and out of the path 80 of said tooth, a friction wheel having an actuating connection with the tone arm of the gramophone, and a drag arm pivoted concentrically with the friction wheel in frictional engagement therewith and connected with the trip arm, said drag arm being movable alternately by the friction wheel and gear tooth toward and from the turn table spindle and adapted to shift the trip arm into and out of the path of the 85 gear tooth as the stylus of the gramophone traverses the spiral groove of a record, and the gear tooth being adapted by engagement with the trip arm to bend the toggle joint and to release the brake lever when the 90 stylus reaches the end of the spiral record groove.
6. In an automatic stop for gramophones the combination with a brake, means tending to apply the brake and means for releasably holding the brake in off position, 100 of a brake controlling member movable into and out of operative position, a friction member connected and movable with the tone arm of the gramophone, a rotary member actuated by the turn table spindle, a drag arm pivoted coaxially with the friction member and disposed radially thereto, said drag arm being supported upon and 105 in loose engagement with said friction member and adapted to be shifted thereby and by said rotary member and to shift the brake controlling member alternately in opposite directions into and out of operative position while the stylus traverses a record 110 groove and the tone arm moves toward the center of the record, and means actuated by the turn table spindle and adapted to shift the brake controlling member and release the brake when the stylus reaches the 115 end of the record groove and the movement of the tone arm is arrested.
- In witness whereof I hereto affix my signature.
- OLE O. STORLE.
